UNITED STATES PATENT OFFICE.

JAMES O. SELBY, OF PORTSMOUTH, OHIO, ASSIGNOR TO UNITED SHOE MACHINERY COMPANY, OF PATERSON, NEW JERSEY, A CORPORATION OF NEW JERSEY.

INSEAM-TRIMMING MACHINE.

SPECIFICATION forming part of Letters Patent No. 788,796, dated May 2, 1905.

Application filed July 16, 1904. Serial No. 216,911.

To all whom it may concern:

Be it known that I, JAMES O. SELBY, a citizen of the United States, residing at Portsmouth, in the county of Scioto and State of Ohio, have invented certain new and useful Improvements in Inseam-Trimming Machines; and I do hereby declare the following to be a full, clear, and exact description of the invention, such as will enable others skilled in the art to which it appertains to make and use the same.

The present invention relates to inseam-trimming machines, and more particularly to inseam-trimming machines adapted for operation upon welted shoes.

The invention is intended primarily as an improvement on the machine disclosed in the patents to French and Meyer, No. 558,379, dated April 14, 1896, and No. 590,831, dated September 28, 1897, but is also applicable to other inseam-trimming machines, and it is to be understood that, except as defined in the claims, the invention is not limited to any particular construction and arrangement of the various parts of an inseam-trimming machine.

The machine disclosed in the patents to French and Meyer above referred to can be used to trim the inseams of welted shoes in a satisfactory manner; but it has been found that considerable care and skill are required to trim the seams closely and uniformly without occasionally cutting so deep as to injure or spoil the shoe. It has also been found in the use of said machine that the projecting edge of the upper along the sides of the shoe is not always trimmed off by the knife, but is turned over against the welt without being cut. This is especially noticeable when the upper is thin and pliable.

The object of the present invention is to provide means particularly applicable to the machine of the French and Meyer patents, but also capable of use in other inseam-trimming machines, whereby the inseam of a welted shoe can be trimmed closely and evenly without liability of injuring or spoil-

ing the shoe and without any special care or skill on the part of the operator.

A further object of the invention is to provide means whereby all portions of the projecting edge of the upper, no matter how thin and pliable, can be trimmed off by the trimming-knife in a certain and reliable manner.

Other objects of the invention are in general to improve the construction and mode of operation of machines for trimming the inseams of welted shoes.

In accordance with the present invention the above objects are secured by the provision in an inseam-trimming machine of a guide arranged to bear upon the edge of the welt of a welted shoe at the side of the upper and regulate the depth of the cut made by the knife. As is well known, the welt of a welted shoe is provided upon its under surface with a groove in which the stitches of the inseam are located, and this groove extends the entire length of the welt at a uniform distance from its inner edge. All portions of the inner edge of the welt are thus located a uniform distance from the stitches of the inseam, and the provision of a guide bearing upon this edge of the welt insures an accurate and uniform trimming of the inseam. The guide bears on a portion of the inseam, so that a careless tipping of the shoe by the operator will not cause the knife to cut the stitches, while an inward movement sufficient to bring the knife in contact with the stitches is absolutely prevented.

Furthermore, the guide is located farther away from the sole than the knife, so that it can extend in the direction of the feed close to or beyond the cutting edge of the knife and bear upon the inseam directly over the point at which the cut is being made. In addition to preventing the trimming-knife from cutting the stitches of the inseam the guide also forms a support for the upper while being cut by the knife and prevents it from being turned over against the welt, so that a thin and pliable upper can be trimmed in as satisfactory a manner as a thick upper. Prefer-

ably the guide is so mounted as to be capable of adjustment to vary the depth of the cut.

The guide above referred to may be used in connection with any suitable devices co-operating therewith to guide the shoe to the action of the trimming-knife, but is preferably used in conjunction with a guide arranged to bear against the sole of the shoe inside of the lip. It is also preferably used in conjunction with a crease-guide arranged to enter the crease between the upper and welt of the shoe, and when such a crease-guide is provided the guide which bears upon the edge of the welt is preferably so mounted that it can be adjusted toward and from the crease-guide in a plane substantially parallel to the plane of the sole, the object of this adjustment being to bring the guide into a position to bear against the edge of the welt at the side of the upper regardless of the distance from the edge of the sole at which the lip is located.

The present invention will be clearly understood from an inspection of the accompanying drawings, in which—

Figure 1 is a view in front elevation of so much of an inseam-trimming machine as is necessary to show the connection of the invention therewith. Fig. 2 is a view in end elevation of the machine illustrated in Fig. 1 with certain parts omitted. Fig. 3 is a detail sectional view showing a shoe in position to be acted upon by the instrumentalities of the machine and illustrating particularly the relative arrangement of the guide which bears upon the edge of the welt, the sole-guide, and the crease-guide. Fig. 4 is a detail view, in front elevation, of the guide which bears against the edge of the welt, and Fig. 5 is a bottom plan view of the guide illustrated in Fig. 4.

The machine illustrated in the drawings, except as hereinafter described, is the same in the construction, arrangement, and mode of operation of its various parts as the machine disclosed in the patents to French and Meyer hereinbefore referred to, reference to which may be had for a complete disclosure thereof.

Referring to the drawings, 1 indicates the cylindrical trimming-knife, 2 the crease-guide, 3 the two-motion feed-jaw, 4 the four-motion feed-jaw, and 5 the sole-guide, these parts being constructed and arranged as in the machine of the French and Meyer patents with the exception that the cutting edge of the trimming-knife is serrated and that the sole-guide is curved adjacent to the cutting edge of the knife and extends within the periphery of the knife and is also so shaped that it bears upon the sole in close proximity to the lip.

In applying the present invention to the machine of the French and Meyer patents a guide 6 has been provided which is arranged

to bear upon the edge of the welt at the side of the upper. This guide is located inside of the periphery of the knife and extends beyond the cutting edge, as is clearly shown in Fig. 1. As illustrated, the guide 6 is adjustably secured to the lower end of a block 7 by means of a screw 8, passing through a slot in the base of the guide, the object of this construction being to enable the guide to be adjusted in a plane at right angles to the cutting edge of the knife to vary the depth of the cut. The block 7 is provided with a vertical slot 9, through which a securing-screw 10 passes and screws into the block 11, from which the sole-guide 5 is supported. This means for securing the block 7 allows the guide 6 to be adjusted toward and from the crease-guide in a plane substantially parallel with the surface of the sole, the object of this adjustment being to bring the guide 6 into a position in which it will bear upon the edge of the welt at the side of the upper when the crease-guide is seated in the bottom of the crease between the upper and welt.

The manner in which the shoe is guided to the trimming-knife will be clearly understood from an inspection of Fig. 3, from which it will be seen that the crease-guide bears against the upper in the crease between the upper and welt. The guide 6 bears upon the edge of the welt at one side of the upper, and the guide 5 bears against the sole inside of the lip at the other side of the upper. The guide 6 bears on a portion of the inseam, so that it is in a position to absolutely prevent an inward movement of the shoe sufficient to cause the knife to cut the stitches uniting the welt and upper to the sole even if the shoe is carelessly manipulated by the operator. The edges of the upper and lining project into the space between the guides 5 and 6, so that they are maintained in a position to be cut by the knife. The knife rotates in the direction indicated by the arrow in Fig. 3, and any tendency of the knife to turn the edges of the upper and lining over against the welt without cutting them is resisted by the guide 6, the side of which bears against the upper and holds it up against the action of the knife.

The object and nature of the invention having been indicated and a specific embodiment of the invention having been illustrated and described, what is claimed is—

1. An inseam-trimming machine, having, in combination, a trimming-knife, and means for guiding a welted shoe comprising a guide arranged to bear upon the edge of the welt at one side of the upper and support the upper while being cut by the knife, substantially as described.

2. An inseam-trimming machine, having, in combination, a trimming-knife, means for guiding a welted shoe comprising a guide arranged to bear upon the edge of the welt at

one side of the upper and support the upper while being cut by the knife, and means for adjusting said guide to vary the depth of the cut, substantially as described.

5 3. An inseam-trimming machine, having, in combination, a trimming-knife, a guide arranged to bear upon the edge of the welt of a welted shoe at one side of the upper and a guide arranged to bear upon the sole at the 10 other side of the upper, substantially as described.

15 4. An inseam-trimming machine, having, in combination, a trimming-knife, a crease-guide arranged to enter the crease between the upper and welt of a welted shoe, and a guide arranged to bear upon the edge of the welt, substantially as described.

20 5. An inseam-trimming machine, having, in combination, a cylindrical trimming-knife and a guide extending within the periphery of the knife arranged to bear against the edge of the welt of a welted shoe and support the upper while being cut by the knife, substantially as described.

6. An inseam-trimming machine, having, 25 in combination, a trimming-knife, a crease-guide arranged to enter the crease between the upper and welt of a welted shoe, a guide arranged to bear upon the edge of the welt and means for adjusting said last-mentioned 30 guide toward and from the crease-guide in a plane substantially parallel to the plane of the sole, substantially as described.

7. An inseam-trimming machine, having, 35 in combination, a cylindrical trimming-knife, a crease-guide arranged to enter the crease between the upper and welt of a welted shoe, a guide extending within the periphery of the knife arranged to bear on the edge of the welt at one side of the upper and a guide arranged 40 to bear on the sole at the other side of the upper, substantially as described.

In testimony whereof I affix my signature in presence of two witnesses.

JAMES O. SELBY.
